SHEET METAL BURIAL VAULT

Henry Walter Robinson, Toronto, Ontario, Canada, assignor to Dominion Manufacturers Limited, Toronto, Ontario, Canada, a company of Canada

Application June 3, 1935, Serial No. 24,600
In Canada June 5, 1934

5 Claims. (Cl. 27—35)

My invention relates to improvements in sheet metal burial vaults of the type known as air sealed vaults, and the object of the invention is to provide means for counteracting the weight of the bell as it is lifted on its hinge and, at the same time, ensure that it is held in a level position when closed to maintain an air seal entirely around the vault between the bell and the base, and it consists essentially of the arrangement and 10 construction of parts as hereinafter more particularly explained.

Fig. 1 is a perspective view of my burial vault.

Fig. 2 is a longitudinal sectional view through the vault and showing the raised position of the 15 vault by dotted lines.

Fig. 3 is a sectional plan view of the vault.

In the drawing like characters of reference indicate corresponding parts in each figure.

1 indicates the vault base made of sheet metal, 20 the central portion 1^x of which is upset inward leaving a surrounding horizontal flange, the portions 2, 3 and 4 being slightly curved up 90° at their outer edges to prevent horizontal movement of the bell and the portion 5 which is turned 180° 25 at its edge to form a semi-cylindrical socket.

6 is the body or bell of the vault provided with vertical walls 7, 8, 9 and 10, the lower portions of which are inclined outward as indicated at 6^x. The portions 6^x of the walls 7, 8 and 9 are turned 30 inward to fit the inwardly turned portions 2, 3 and 4 of the base terminating at its inner edge in a vertical flange 6° which, at the free end of the bell, is utilized as an engaging portion for the lock hereinafter described. The portion 6^x of the wall 10 is formed into a segment of a circle greater than a semicircle and which fits into the 35 semicircular portion 5 to function as a hinge pin. 11 are leaf springs secured to the base and bearing against the hinged end wall of the bell adjacent 40 each side of the bell. 12 are latch locks secured in the opposite end of the base substantially in a line with the springs 11.

Normally, when the bell is first set in position, it is held by the springs 11 in a slightly upwardly 45 inclined position clear of the latch lock 12 secured to the base 1 to permit the bell being gripped at its front end and raised with the aid of the springs 11 to the full open position indicated by dotted lines in Fig. 2. When the bell is in this position it is supported by the strut 13 which engages the notch 14^x in the block 14. As the bell is lifted the free end of the strut slides up the incline 14° into the notch 14^x at it is drawn rearwardly by the spring 15 against the shoulder 14¹. 55 By lifting the bell further so that the free end of

the strut rises above the shoulder 14¹, the spring 15 again acts to pull the strut 13 rearward finally when the bell is again lowered carrying the strut into the dotted position 13^x. As the bell is lowered and the strut carried to the position 13^x, 5 the lower end of the flange 6° of the bell engages the latch locks 12 to force it inward so that as the bell is forced downwardly against the lift of the spring 11 the latch locks spring over the upper edge of the flange 6° as shown in Fig. 2 locking 10 the bell down. The latch locks 12 being adjacent each side of the bell, the lower edge of the bell is held level when the bell is in the closed position parallel with the base so that an air seal is maintained all around the bell. 15

When moisture tends to enter the bell, it rises between the bell wall and the portion 1^x of the base compressing the air within the bell until equilibrium takes place between the rising moisture and compressed air which prevents the 20 moisture rising further into contact with the coffin. A spring being located at the end towards each side of the vault and latches at the opposite end of the vault opposite each spring ensures 25 of the vault not tipping laterally but remaining 25 level so that there is no danger of the compressed air escaping to decrease the pressure and allow of the water or other moisture rising to the casket level.

The functioning of the springs and latches 30 coact together to maintain the lower edge of the vault bell in a level position so that one side of the bell cannot rise in relation to the other side so as to permit the air escaping beneath the edge of the bell which is raised and thus allow the 35 moisture to rise further into the vault as above described.

From this description it will be seen that I 40 have devised, in a vault of air sealed type, a body or bell which is hingedly mounted at one end to the base without the use of hinge pins, which provides means for counterbalancing the major portion of the weight of the bell during the lift so as to make it easy to lift with a minimum amount of effort, and in which the means for 45 operating the strut support is hidden from view and operates said support smoothly and silently.

What I claim as my invention is:—

1. In a burial vault, a base, an undivided bell having a wall at each end, one of which is hinged 50 at its lower end to the base, a lip extending inwardly from the lower edge of the opposite end wall, a pair of spring latches carried by the base at the opposite end to the hinge and adjacent each side of the base and engaging the lip, and 55

- leaf springs carried by the base at the hinge end and in alignment with the latches and bearing against the corresponding end wall of the bell above the hinge.
5. 2. In a vault construction of the class described having a base portion, a bell portion pivotally connected at one end thereof to the base portion and latching means adapted to secure said bell and base portions together, means associated 10 with said portions at one end thereof and cooperating with said portions to aid in opposing the weight of said bell portion when it is to be raised about its pivotal end to permit of the reception of a casket upon said base portion.
15. 3. In a vault construction of the class described having a base portion, a bell portion pivotally connected at one end thereof to the base portion and latching means adapted to secure said bell and base portions together, spring means cooperating with said bell and base portions at the pivotal end thereof to oppose the weight of said bell portion when it is to be raised about its pivotal end to permit of the reception of a casket upon said base portion.

4. In a vault construction of the class described having a base portion, a bell portion pivotally connected at one end thereof to the base portion and latching means adapted to secure said bell and base portions together, a pair of flat springs 5 anchored to said base portion and engaging an end wall of said bell portion at the pivotal end to permit of the reception of a casket upon said base portion.

5. In a vault construction of the class described 10 having a base portion, a bell portion pivotally connected at one end thereof to the base portion and latching means adapted to secure said bell and base portions together, a pair of flat springs anchored to said base portion and en- 15 gaging an end wall of said bell portion at the pivotal end to permit of the reception of a casket upon said base portion, said springs being mounted in a position one each opposed to each latch whereby the bell is brought to rest evenly on the 20 base at all sides.

HENRY WALTER ROBINSON.
